UNITED STATES PATENT OFFICE.

HELEN J. MILLER, OF BUFFALO, NEW YORK.

GAME APPARATUS.

Application filed January 25, 1922. Serial No. 531,817.

To all whom it may concern:

Be it known that I, HELEN J. MILLER, a citizen of the United States, residing in Buffalo, in the county of Erie and State of New York, have invented new and useful Improvements in Game Apparatus, of which the following is a specification.

This invention relates to a game apparatus in which different characters or combinations of characters are obtained through the skill of a player by whirling one or more marbles upon the surface of a hand operated disk so that the marble or marbles, as the case may be, will enter one or another of an annular row of pockets corresponding to designating characters on the adjacent parts of the disk.

It is the object of this invention to provide a simple apparatus of this character which is instructive and entertaining and which can be adapted to give information as to numbers, words, politics, history and other educational matter.

In the accompanying drawings: Figure 1 is a top plan view of my improved game apparatus. Figure 2 is a vertical cross section of the same taken on line 2—2, Fig. 1. Figure 3 is a horizontal section taken on line 3—3, Fig. 2.

Similar characters of reference refer to like parts throughout the several views.

In its general organization this game apparatus comprises a base 10, a disk 11 or bowl which is pivotally mounted on the base 35 so as to be capable of rotation about a vertical axis, and one or more marbles 12, 13 which are adapted to be whirled from the central part of the disk toward the periphery thereof by contact with the upper surface of 40 the disk while the latter is rotating.

The base preferably has a flat underside whereby the same may rest on a table or other support and on its upper side the same has an upwardly projecting pivot pin 14 45 which comes to a point and serves as part of the means for pivotally supporting the disk on the base.

Although the disk may be variously constructed the same is preferably of circular form and has its upper side 15 dished downwardly or made of bowl shape or concave form so that the same gradually rises from the low part at the center thereof to the high part at the margin of the same. On 55 its central part the disk is provided with an

upwardly projecting hub 16 of cylindrical form and this is pivotally mounted on the pivot pin by means of a bushing 17 of hardened metal or other material secured in an opening 18 in the hub and provided on its underside with a downwardly opening socket 19 which receives the upper end of the pivot pin. On its upper end the bushing is provided with a knob or finger piece 31 whereby the disk may be manipulated so as to cause the same to spin or turn rapidly on the pivot pin of the base about a vertical axis. At the margin of the disk the same is provided with an elevated rim extending around the circumference of the same which rim is provided with a plurality of pockets 20 arranged in an annular row. Each of these pockets is open at the top and has an inlet on its inner side which opens toward the axis of rotation of the disk. The upright walls 21, 22 of each of these inlets are arranged at an angle to a radial line from the axis of the disk and these walls of the several pockets all trend in the same backward direction. The bottom 23 of each pocket is depressed slightly below the adjacent upper surface of the disk so that a marble entering this pocket will be retained therein while the disk is turning forwardly.

Upon the upper annular surface of the rim adjacent to the pockets are arranged suitable designating characters which have interesting, entertaining and instructive value and which are utilized for determining the winner of a game when playing with this apparatus. As an example of suitable designations, names, or abbreviations 24 of one or more of the several States of the United States are placed in the section on the rim corresponding to each pocket, the congressional vote apportioned to each State is indicated at 25 in connection with its name, and numerals 26 representing the total congressional votes of one or more States in the respective sections are associated with the same.

In playing this game one or more marbles or balls may be used and the players can take turns in spinning the disk or the same party can do the spinning for the several players, as previously agreed upon.

As an example of one way in which this game may be used, let it be assumed that two players each elect one of the two marbles shown in Fig. 1, these marbles being dis-

tinguished from each other by color, shading or otherwise, the same being shown as black and white respectively in the drawing. When beginning the game, the marbles are 5 placed in the central part of the disk and then the first player grasps the knob or finger piece by the hand and turns the same forwardly in the direction of the arrow in Fig. 1, so that the disk turns rapidly for 10 a while without further attention on the part of the operator. Due to the frictional contact of the upper surface of the disk with the marbles a whirling action is imparted to the same and owing to the centrifugal force to which the marbles are subjected, the same gradually travel outwardly and upwardly on the rising concave surface of the disk until they are eventually thrown into one or another of 15 the pockets of the rim. The particular pockets which are entered by the marbles selected by the player determines the count which is placed to the credit of the respective player, which count in this instance 20 consists of the electoral votes represented by the States in the section corresponding to those in which the marbles have entered. The marbles after once entering the pockets can not escape therefrom while 25 the disk is turning forward or while the same is at rest, inasmuch as the inclined rear wall 21 of each inlet by its wedging or cam action tends to force the marble outwardly while the disk turns forwardly and thus retains the marble in the pocket while 30 the depressed bottom of the pocket prevents the marble from rolling out of the same to the low part of the disk. The marbles thus remain in place on the respective pockets 35 when the disk ends its forward rotation and remains at rest and permits of accurately observing the result.

Preparatory to making the next play the disk is first turned backwardly a short distance or in a direction opposite to that indicated by the arrow which causes the inclined front wall 22 of each pocket to act as a cam on the marble therein and to eject the same inwardly from the pocket to the inner low part of the disk ready for 40 operation by the next player. After a predetermined number of innings by the respective players the successive counts are added to determine the respective scores of 45 the players and the winner of the game.

It will be noted that at no time is it necessary to handle any of the marbles, inasmuch as the marbles are automatically thrown outwardly into the pockets by centrifugal force and also ejected inwardly 50 therefrom by the cam action of the rear walls of the pockets. If desired, access to the marbles may be positively prevented by placing a transparent cover 27 of glass or 55 the like over the cavity and pockets in the

disk and securing the same thereto by screws 28 or other suitable fastenings.

In order to add further interest to the game, one of the indicating sections may be designated in a manner to denote a loss in 70 the count, for example, in section 40 a star is shown in connection with the words "Presidential veto" which may indicate a negative count equivalent to losing the particular play when the marble enters the 75 pocket of this designation.

Obviously any other suitable characters or system of play may be used which will create interest and entertainment, but in all cases the essence of this invention would 80 be present.

For the purpose of permitting the turning of the disk to be promptly arrested in a convenient manner when the marbles have entered the pockets, a brake device is provided which preferably consists of a brake lever 29, the inner end of which is arranged between the upper side of the base and the outer end adjacent to the periphery of the disk. This lever may be held in 85 place by any suitable means, for instance, by providing its inner part with a longitudinal slot or elongated opening 30 which receives the pivot pin. Normally, this lever is arranged loosely between the disk and base, so that the bushing of the disk rests 90 solely on the pivot pin of the base and can turn freely without interference from the brake lever. When, however, it is desired to stop the rotation of the disk, the outer 95 end of the lever is depressed which causes the intermediate part thereof to turn on the base as a fulcrum and the inner end of the same to lift the disk from the pivot pin, thereby applying increased frictional 100 resistance to the disk and quickly bringing the same to a state of rest. The several parts of the apparatus, except the glass cover, are preferably made of metal, although any other suitable material may be 105 used.

In order to permit of starting the whirling action of the marbles promptly when spinning the disk or bowl the hub 16 is provided on its periphery with vertical serrations or corrugations 32, as shown in Fig. 1, which take hold of the marbles and cause them to effect their initial movement with the disk before being thrown away 115 from the same by centrifugal force.

This game device is not only very entertaining but the same is also very attractive and amusing owing to the manner in which the same operates.

I claim as my invention:

1. A game apparatus comprising a base, a disk adapted to turn about a vertical axis on said base and having a peripheral rim the inner side of which is provided with a plurality of pockets, each of which has an 120 130

inlet on its inner side the walls of which are arranged at an angle to a radial line from the axis of rotation of the disk.

2. A game apparatus comprising a base having an upwardly projecting pivot, a disk adapted to rotate about a vertical axis and provided on its marginal rim with an annular row of inwardly opening pockets and provided centrally on its underside with a downwardly opening socket which receives said pivot pin, a marble adapted to be whirled by contact with the upper surface of the disk into one or another of said pockets, and a brake for arresting the rotation of said disk consisting of a lever having its inner part interposed between the underside of said disk and the upper side of said base.
3. A game apparatus comprising a base having an upwardly projecting pivot, a disk adapted to rotate about a vertical axis and provided on its marginal rim with an annular row of inwardly opening pockets and provided centrally on its underside with a downwardly opening socket which receives said pivot pin, a marble adapted to be

whirled by contact with the upper surface of the disk into one or another of said pockets, and a brake for arresting the rotation of said disk consisting of a lever having its inner part interposed between the underside of said disk and the upper side of said base, and provided with an opening which receives said pivot pin.

4. A game apparatus comprising a base, a disk adapted to turn about a vertical axis on said base and having a dished upper surface which is low at the center of the disk and high at the margin thereof and having a marginal rim which projects upwardly from the disk and has a circumferential row of pockets which have inlets opening toward the axis of the disk, and a marble adapted to be whirled by contact with the upper surface of the disk into one or another of the pockets thereof, the bottoms of said pockets being depressed below the adjacent surface of the disk, and the inlet of each pocket having its walls arranged at an angle to a radial line from the axis of the disk.

HELEN J. MILLER.
